SUPPORT FOR TABLE TENNIS NETS

Filed Dec. 15, 1945

UNITED STATES PATENT OFFICE

2,470,318

SUPPORT FOR TABLE TENNIS NETS

Samuel Nadelson, New York, N. Y.

Application December 15, 1945, Serial No. 635,139

2 Claims. (Cl. 273—30)

1

This invention relates to supports for nets, and particularly nets of the character used for playing tennis, table tennis or other games wherein a net is required to be stretched across the playing area.

In table tennis games, the net employed is usually supported at its opposite ends by the upright posts of brackets which are clamped to the table in such a manner that the upright posts arise above the table. Bolts or similar threaded elements are customarily used for engaging the ends of the net, such bolts extending through apertures in the posts, and by operation of wing-nuts on the bolts, the net is drawn taut between the posts. Such an arrangement requires manual adjustment from time to time; the ends of the bolts with the nuts thereon project from the posts in such a manner that the players are likely to be injured by contact with the same. Moreover, the manual adjustment of these parts, if not properly performed, only tends to impose too much strain on the net, or else allows undue slack in the net. An object of the present invention is to provide a support for use at each end of the net which will engage the net and apply a resilient pull or tension thereon so that the net will always be held with the proper degree of tautness across the table.

The invention further contemplates the provision of means by which the resilient pull imposed on the net will be applied directly longitudinally of the net and will tend to automatically take up any slack therein, thus compensating for variation in the lengths of nets often due to stretching, weather condition and other causes.

Still another object of the invention is to provide a support of the character described in which the projecting elements, likely to cause damage or injury to the players, are dispensed with.

In the accompanying drawing, wherein several embodiments of the invention are disclosed, Fig. 1 is front elevation of one of the supports, showing a portion of the net attached to the same; Fig. 2 is a sectional view on the line 2—2 of Fig. 1, looking in the direction of the arrows; Fig. 3 is a sectional view on the line 3—3 of Fig. 1, looking in the direction of the arrows; Fig. 4 is an enlarged sectional view of the ends of the leaf spring and rod engaged thereby; Fig. 5 is a side elevation of a modified structure, and Fig. 6 shows another modification.

With reference to the embodiment of the invention shown in Fig. 1, the supporting bracket is generally indicated at 1. This bracket is preferably, but not necessarily, constructed of flat

metal strip stock of substantial thickness to thereby form a rigid support. It is formed with a foot portion 2 which rests upon the top of the playing table 9, said foot portion being secured, as by being welded, to the top of a C-shaped clamp 4 having a lower element 5 through which a clamping screw 6 is threaded. Said clamping screw is provided with a head 7 for engagement against the under side of the table 9, whereby the table will be thus clamped between the head 7 of screw 6 and the top element 8 of the C-clamp 4, said portion 8 of the clamp being fixedly secured to the foot 2 of the bracket as heretofore explained.

15 The bracket includes an upstanding post 3 preferably formed integrally with the foot 2, said post acting to support an end of the net 10 through resilient means to be described. Said resilient means includes a leaf spring having a central flat portion 16 contacting with the inner face of the post 3 and being fixedly secured thereto by the two rivets 17 or other equivalent fastening elements. Extending from the flat central portion of the leaf spring is a pair of arched or bowed arms 15 which may be formed integrally with the central part of the spring. The curved shape of these arms 15 of the spring is such that the same tend to bear toward the inside face of the post, or in other words to exert a pull on the net longitudinally in a direction toward the post. Each of the arms 15 of the spring has its free end laterally bent as indicated at 13, each of said laterally-bent ends 13 being provided with an aperture 18.

335 Shown at 12 is a rod or bar having studs 14 at its opposite ends, said studs being removably fitted into the apertures 18 in the laterally-bent ends 13 of the spring arms 15. The ends 13 are slightly sprung toward one another so that when the bar is placed between them, and with the studs 14 on the ends of the bar or rod placed in the apertures 18, the rod or bar 12 will be securely held in place, but can be easily removed by flexing the spring arms to disengage the lugs 45 from the apertures 18.

In the form shown, the net is provided at each end with a hem 11 constituting a pocket fitting around the rod. When the net has been fitted at each of its ends with one of the rods 12, and the rods placed in position between the ends of the spring arms, the tendency of the spring arms to exert a pull toward the spring post to which they are secured, will draw the net longitudinally and thus hold it taut across the table. Since the springs can be flexed to a considerable extent, it

will be obvious that variations in the lengths of the nets provided can be compensated for and the nets used will always be held taut. When it is desired to remove a net, the rods 12 at the opposite ends of the net are simply removed from the springs, and a replacement of the net means merely slipping the rods back into place, the springs acting at once to take up the slack in the net without requiring any manual adjustments.

It is to be noted that the springs and the rods supported thereby are attached to the inside faces of the upright posts 3 so that the outer face of the post is smooth and clear of projections. Thus, the likelihood of a player injuring himself on protruding parts is completely obviated.

In the embodiment of the invention shown in Fig. 5, the rod 12 is held between the laterally-bent ends 21 of a bracket 20, which might be of springy or resilient material, and extending from the bracket is one or more, and in the embodiment shown, two pins or studs 22 which slide through apertures provided in the upright post 3 of the supporting bracket. On the end of each of the pins or studs 22 is a head or nut 24, and confined between the head or nut 24 and the outer face of the upright post 3 is a coil spring 23 extending around the pin 22. Through this arrangement, a resilient pull is imposed on the rod 12 and the end of the net through which the rod is fitted. While the structure shown in this embodiment of the invention causes projecting elements to become disposed on the outside of the post 3, the shape and disposition of such elements is such that the same can be readily protected by suitable rubber shields or sleeves, not herein shown, in order to more clearly disclose the construction.

In the embodiment of the invention shown in Fig. 6, a rod 25 is shown as extending through the hem 11 of the net, said rod being provided at its opposite ends with an eyelet 26. A spring 27 has one end attached to the eyelet and its other end secured to the post 3, the springs tending to pull the end of the net toward the post. While two springs 27 are shown, this number may be increased if desired.

While I have shown several embodiments of the invention, other embodiments and changes in the disclosed structures will be readily apparent to those skilled in this art. In the disclosed structures, the net is drawn taut with the imposition of a resilient pull on its opposite ends. The result is that all slackness in the net is taken up, differences in net-lengths is compensated for, manual adjustments are rendered unnecessary and setting up and taking down of the net is greatly simplified.

I have herein suggested that the net employed might be provided at its ends with a hem to form an elongated pocket to fit the rod 12, but it will be understood that strings of the character used on some types of nets can be used to attach the nets to the rods or possibly directly to the spring arms 15. It is also possible to facilitate the placement of the stub-ends of the rods into the apertures 18 by the provision of grooves in the ends of the spring arms adjacent to the apertures and whereby the ends of the rod may be easily snapped into the apertures and readily manually removed from engagement therewith.

These and other modifications are comprehended as being within the scope of the invention and the claims appended hereto.

What I claim is:

1. A net holder comprising, a bracket having an upright post, a leaf spring secured to the inner face of the post, said spring having a pair of resilient arm portions bowed or shaped to cause the same to extend toward the inner face of the post, lateral ends on said arm portions extending in a direction away from the post, a rod holding one end of a net, said rod being resiliently clamped between the lateral ends of the spring arms, said ends being apertured to receive the ends of the rod.

2. A net holder comprising, a bracket having a rigid upright post, a flat leaf spring located on the inner face of the post, said spring being rigidly and non-pivottally attached at a substantially central point to the inner face of the post, said spring having a pair of resilient arm portions bowed or shaped to cause the same to extend toward the inner face of the post, lateral ends on said arm portions extending in a direction away from the post, a rod holding one end of a net, said rod being resiliently clamped between the lateral ends on the spring arms, said ends on the spring arms being apertured to receive the ends of the rod, and the rod having its ends reduced in diameter to fit the apertures in the ends of the spring arms.
